ASH TRAY

Edward T. Peters, Boulder, Colo.

Application December 30, 1953, Serial No. 28,291

Term of patent 3½ years

(Cl. D85—2)

To all whom it may concern:

Be it known that I, Edward T. Peters, a citizen of the United States, residing at Boulder, county of Boulder, State of Colorado, have invented a new, original, and ornamental Design for Ash Tray, of which the following is a specification, reference being had to the accompanying drawing, forming a part hereof.

Figure 1 is a top plan view of an ash tray, showing my new design; and,

Figure 2 is a section taken on line 2—2 Figure 1.

I claim:

The ornamental design for an ash tray, as shown.
